Original application July 2, 1963, Ser. No. 292,222. Di-
vided and this application Jan. 15, 1965, Ser. No.
425,810

3 Claims. (Cl. 84—307)

This invention relates to bridges for stringed instruments such as guitars and the like.

This application is a division of application Serial No. 292,222, filed July 2, 1963.

In the prior art there have been many types of bridges for stringed instruments, some of which have proven more satisfactory than others, but none have been particularly satisfactory when used on stringed instruments employing tremolo devices to provide ease in tremolo manipulability, and to assist in the maintenance of tremolo tone quality.

The primary object of the invention is to provide an improved swinging suspension bridge for stringed instruments which assures long playing of the instrument without becoming out of tune, which improved bridge is particularly useful in stringed instruments equipped with a tremolo device.

A further object of the instant invention is to provide an improved and simplified suspension bridge for guitars and other stringed instruments which does not alter the normal tone quality of the musical instrument with which it is employed; the said suspension bridge being self-positionable to compensate for normal string shortening and string lengthening occurring during the playing thereof.

Other objects of the invention will become apparent by reference to the following detailed description taken in connection with the accompanying drawing, in which:

FIG. 1 is an enlarged fragmentary plan view of a guitar having thereon a swingable suspension bridge embodying the invention, the said guitar being equipped with one preferred type of tremolo device.

FIG. 2 is a longitudinal sectional view taken on the line 2—2 of FIG. 1.

FIG. 3 is an overall plan view of a tremolo equipped guitar showing thereon a swingable suspension bridge of the invention.

FIG. 4 is an enlarged sectional view taken on the line 4—4 of FIG. 1.

FIG. 5 is an enlarged elevational view taken on the line 5—5 of FIG. 1.

FIG. 6 is an enlarged sectional view taken on the line 6—6 of FIG. 1.

FIG. 7 is an enlarged sectional view of the swingable suspension bridge of the invention taken substantially on the line 7—7 of FIG. 1.

FIG. 8 is a sectional view taken on the line 8—8 of FIG. 7.

FIG. 9 is a sectional view taken on the line 9—9 of FIG. 7.

Referring now to the drawings wherein like reference characters refer to like and corresponding parts throughout the several views, a preferred embodiment of the improved swingable suspension bridge 50 of the invention useable on stringed instruments is disclosed in the drawings for illustrative purposes mounted on a guitar 12. The guitar 12 or other conventional stringed instrument with which the instant invention may be employed generally consists of a body 13, neck 14 including frets 15, a neck bridge 16, a head 17, and the usual adjustable key operated string anchor pegs 18. Strings 19 anchored at one end to the tail piece 20 of the tremolo device 10, and,

2

as hereinafter described in detail, the said strings 19 are supported on the special improved suspension bridge 50. The said improved suspension bridge 50 has its base 51 fixed to the top member 130 of the body 13 of the guitar 12 by suitable countersunk head studs 52. The other end 5 of the said strings 19 are suitably anchored to conventional string anchor pegs 18 extending into the head 17 on the neck 14.

It is important to note that the suspension bridge 50 of the instant invention provides a marked improvement in the sensitiveness of response to fingering during play of stringed instruments over such instruments equipped with earlier bridges. Also, when the improved bridge 50 is used on stringed instruments equipped with spring centered tremolo devices such as the tremolo device 10 shown in the drawings and described herein, the effectiveness of the tremolo mechanism has been found to be an aid to the self-centering of the tremolo device in that the normal string pressure on the bridge constantly urges the bridge 15 to swing back to center after release of manipulation of the operating lever of the tremolo device, which urging is in aid of and not opposed to the functioning of the tremolo device. This does not occur when using conventional fixed, pivoted or roller bridge heretofore employed with tremolo devices.

The tremolo device 10 disclosed herein for illustrative purposes consists of a base plate 11 fixed to the top member 130 and end member 131 of the guitar body by suitable studs or the like 21. A pair of laterally spaced upstanding posts 22 preferably formed integral with the said base 11 are suitably bored and threaded at 23 to receive studs 24 which telescope through the transverse ends 252 of the hour glass shaped tremolo spring 25 and secure it to the said base 11 in spaced relationship thereabove and 20 above the top member 130 of the said guitar body 13. The said tremolo spring 25 is preferably substantially rectangular in cross section and has a head end 250, and symmetrical inwardly curved sides 251, and transverse ends 252. The tail piece 20 which receives and anchors the ends of the strings 19 at the head end 250 of the tremolo spring 25 is suitably fixed thereto. Obviously, the tail piece 20 may be omitted, and the strings 19 may be suitably fixed to the head end 250 of the tremolo spring 25.

The said tail piece 20 and the head end 250 of the tremolo spring 25 are centrally bored to telescopingly receive a long adjusting stud 26 having its head end and lower end threaded at 260 and 261 respectively. The said lower end 261 of the adjusting stud 26 is threaded into an anchor arm 27 which is pivotally connected at 28 to a tremolo lever 29 pivoted at 30 to the base 10 as best shown in FIG. 1. The free end of the tremolo lever 29 is suitably bored at 31 to receive the lower end 320 of the tremolo arm 32 having an operating handle 33 at the upper end thereof. Suitable lock nuts 262 and 263 on each threaded end 260 and 261 of the adjusting stud 26 fix the tremolo spring and lever mechanism in their proper adjusted position. A suitable set screw 34 may be employed to fix the tremolo arm 32 in a desired adjusted position.

The pivot 28 connecting the anchor arm 27 to the tremolo lever 29, and the pivot 30 connecting the tremolo lever 29 to the base 11, are both preferably ball bearing pivots to assure completely free operation of the tremolo device 10. By shortening or lengthening the distance 65 between the head end 250 of the tremolo spring 25 and the anchor arm 27 by means of the adjusting stud 26, the normal operating characteristics of the tremolo device 10 and its tremolo spring 25 are established, and by turning up the lock nuts 262 and 263 on the threaded head and lower ends 260 and 261 respectively of the adjusting stud 26, such adjustment is maintained.

The particular novel swinging suspension bridge construction 50 of the invention is preferably employed in combination with a tremolo device 10 or other suitable tremolo device, and consists of a base 51 which is secured by means of countersunk head studs 52 at the proper location to the top member 130 of the body 13 of a guitar or the like 12. Upwardly extending from opposite ends of the base 51 are suitable stanchions 510 bored and threaded at 511 to receive threaded semispherically headed Allen type studs or posts 53 which may be turned to level or support the bridge suspension bar 55 at the desired height above the base 51.

The bridge suspension bar 55 is generally U-shaped having a low platform 550, end uprights 551 and outwardly disposed flanges 552. Each outwardly disposed flange 552 is apertured at 553 and formed at the said apertures 553 to conform to the curvature of the round head studs or posts 53 providing a universal joint 56 between the flanges 552 of the bridge suspension bar 55 and its supporting posts 53.

A generally triangular string supporting bridge element 60 is mounted by such means as studs 61 centrally on the top of the low platform 550 of the bridge suspension bar 55. The said bridge element 60 is suitably notched at 62 to accommodate the strings 19 of the guitar or other stringed instrument 12.

With the foregoing novel construction, the suspension bridge 50 of the invention is positively self-returning to neutral after manipulation of the tremolo device's operating arm 32 and release of the tremolo operating handle 33, the movement of the operating arm 32 of the tremolo device 10 minutely alternately shortening and lengthening the strings 19 of the musical instrument to obtain the tremolo effect. The downward pressure of the strings 19 on the swinging suspension bridge 50 constantly urges the bridge 50 to swing back to its central or neutral position from which it swings during the manipulation of the particular tremolo device that may be employed.

Obviously, the new and improved suspension bridge 50 of the invention may be used on stringed instruments either alone or in combination with any tremolo device including but not limited to the tremolo device 10 whereby to provide a highly effective easily accomplished full toned tremolo effect. When the novel suspension bridge 50 is used on a stringed instrument without a tremolo device, the response to fingering the instrument during play is highly sensitive. When the said novel suspension bridge 50 is used in combination with a conventional tremolo device the usual frequent re-tuning of conventional tremolo equipped instruments during long periods of play is not required.

Although but a single embodiment of the invention has been disclosed and described in detail, it is obvious that many changes may be made in the size, shape, arrangement and detail of the various elements of the invention, all without departing from the spirit and scope thereof as defined by the appended claims.

We claim:

1. In a stringed musical instrument, a swingable suspension bridge including a base fixed thereon transversely of and below the strings of said stringed instrument, said base having stanchions at opposite ends thereof, a bridge suspension bar including a low platform, end uprights and outwardly disposed end flanges sup-

ported on said stanchions and formed to provide universal movement therebetween, and a triangular string supporting element disposed longitudinally on said low bridge platform and fixed thereto, the said suspension bridge platform and said string supporting element swinging longitudinally with movement of the strings supported thereon during playing of the said instrument.

2. In a stringed musical instrument, a swingable suspension bridge including a base fixed thereon transversely of and below the strings of said stringed instrument, said base having stanchions at opposite ends thereof, semi-spherically headed studs threaded into said stanchions and extending thereabove, a bridge suspension bar including a low platform, end uprights and outwardly disposed end flanges formed to be supported on said studs and provide a universal movement between said bridge suspension bar and said studs, the turning of said studs providing means for leveling and adjusting the height of said bridge suspension bar in respect to the said base and stanchions, and a string supporting element on the low bridge platform of said bridge suspension bar supporting the strings of said instrument below the points of universal support of said bridge suspension bar, the said suspension bridge platform and said string supporting element swinging longitudinally responsive to movement of the strings supported thereon during play of the said instrument.
3. A swingable suspension bridge for stringed musical instruments provided with a spring centered manually operated tremolo device comprising a base fixed on said instrument transversely of and below the strings thereof, said base having stanchions at opposite ends thereof, semi-spherically headed studs threaded into said stanchions and extending thereabove, a bridge suspension bar including a low platform, end uprights and outwardly disposed end flanges formed to be supported on said studs and provide a universal movement between said bridge suspension bar and said studs, the turning of said studs providing means for leveling and adjusting the height of said bridge suspension bar in respect to the said base and stanchions, and a string supporting element on the low bridge platform of said bridge suspension bar supporting the strings of said instrument below the points of universal support of said bridge suspension bar, the said suspension bridge platform and said string supporting element swinging longitudinally with the movement of the strings supported thereon responsive to manual operation of the tremolo device and the fingering of the said instrument.
